UNITED STATES PATENT OFFICE.

JOSEPH FAWELL, OF PITTSBURG, PENNSYLVANIA.

ROLLING-MILL.

946,794.

Specification of Letters Patent. Patented Jan. 18, 1910.

Application filed July 1, 1908. Serial No. 441,375.

To all whom it may concern:

Be it known that I, JOSEPH FAWELL, residing at Pittsburg, in the county of Allegheny and State of Pennsylvania, a citizen 5 of the United States, have invented or discovered a certain new and useful Improvement in Rolling-Mills, of which improvement the following is a specification.

The invention described herein relates to 10 certain improvements in rolling mills embodying two stands of horizontal rolls, which are respectively driven in opposite directions and one or more stands of vertical rolls, two series of driven feed rollers arranged to feed 15 to the respective stands of horizontal rolls and means for transferring the article being rolled from one series of feed to the other.

The invention is hereinafter more fully described and claimed.

20 In the accompanying drawings forming a part of this specification Figure 1 is a plan view of a mill embodying my improvements; Fig. 2 shows side elevations illustrating the arrangement of the two stands of horizontal 25 rolls. Fig. 3 is a sectional view on a plane indicated by the line III—III Fig. 1. Fig. 4 is a plan view illustrating a modification of the mill shown in Fig. 1. Fig. 5 is a sectional diagram the plane of section being indicated by the line V—V Fig. 4. Fig. 6 is 30 a plan view illustrating a further modification of my improved mill; Fig. 7 is a plan on an enlarged scale of the rolls and feed rollers shown in Fig. 6 and Fig. 8 is an ele- 35 vation of a housing used in the mill shown in Figs. 7 and 8.

In the mill shown in Figs. 1 and 5, inclusive, I employ two stands A and B of horizontal rolls arranged out of line with each 40 other, but in such proximity as will permit of the easy transfer of the article being rolled from the delivery side of one stand, as A, to the feed side of the other stand of rolls B. In connection with these two stands 45 of horizontal rolls, I employ vertical rolls arranged respectively in suitable relation with two stands of horizontal rolls.

In the arrangement shown in Figs. 1, 2 and 3, provision is made for driving both 50 stands of horizontal rolls and the vertical rolls from a common motor D through suitable trains of gearing constructed and arranged to rotate the rolls of stand A to feed the article in one direction and rolls of the 55 stand B to feed in the opposite direction. As shown in Figs. 1, 2 and 3, two series of

feed rollers 2 and 3, are arranged respectively on opposite sides of the mill and are independently driven by reversible means, so that each series will act at one time to deliver the article and when reversed to receive the article being rolled. While the vertical rolls might be arranged in two separate stands, it is preferred to employ the arrangement shown in Fig. 1, consisting of an intermediate vertical roll 4 and two outside vertical rolls 5 and 6, the central roll is arranged so that its periphery will extend into the line of movement of the article delivered from the stand of rolls A and also into the line of delivery of the article from the stand of rolls B, so that the same rolls can be used for edging articles passing through these two stands without any reversal of its direction of rotation. Provision is made by 60 means well known in the art for adjusting the outer rolls 5 and 6 toward and from the intermediate vertical roll. The vertical rolls are driven from the motor E through a suitable shaft, the roll 5 being driven so as to have a peripheral movement in the same direction as the roll A, while the roll 6 has a peripheral movement in the direction of rolls B. By reference to Figs. 1, 2 and 3 it will be seen that in case the stand of rolls A were 65 formed by two horizontal rolls, the driving connection to the lower roll would interfere with the feed of articles being delivered by the stand of rolls B. In order to overcome this objection three-high rolls are employed 70 in stand A, the intermediate roll being driven by frictional contact with the lower roll. This arrangement permits of the driving connection of the lower roll passing below 75 the feed rollers 2.

In lieu of using an intermediate roll as shown in Figs. 2 and 3, in order that an article may pass out along the feed rollers 2 from the vertical rolls, the two stands of horizontal rolls may be independently 80 driven, or driven by independent motors, as indicated in Fig. 4, the couplings 7 for the stand of rolls A extending out on one side of the mill and those for the stand of rolls B extending out from the opposite side of 85 the mill. In this construction the journals on the inner ends of the lower rolls are provided with studs or projections 8 which extend beyond the center housings and form journal pins for one of the rollers as 2^a or 3^a 90 of each series. These rollers are provided with journals at their opposite ends on 95 100 105 110

which are secured gear wheels 9 so as to permit their being driven by the motor or motors 10 driving the other rollers of the series. As will be readily understood, these 5 rollers 2^a and 3^a are rotated in the reverse direction to that of the rolls by which they are supported.

In the arrangement shown in Fig. 4 the vertical rolls may be driven by an independent motor if desired, or the shaft 11 10 for driving these vertical rolls may be extended out on each side of the mill and be connected by suitable gearing to the motors driving the horizontal rolls. In such an arrangement while an article is passing through the stand A and the vertical rolls in line therewith these two stands of rolls, i. e., the horizontal and vertical, will be driven by a common motor which will also 15 be assisted by the motor employed for driving the stand of rolls B, the latter running idle at this time.

In using the mills shown in Figs. 1 and 4 the article is placed upon the feed table 2 20 and is fed thereby in between the rolls of stand A and the vertical rolls in line therewith. When the article has passed beyond the housings of the vertical rolls the motors of the feed tables are stopped and the ingot 25 shifted by the head or abutment 12 over to line with the stand of rolls B and its vertical rolls. The feed rollers are now rotated in the opposite direction so as to feed the article into the rolls B through the vertical 30 rolls into position where it can be again shifted in the opposite direction by the head 12^a. It will be observed during this operation that although the article is moved in opposite directions there is no reversal of 35 any of the rolls either horizontal or vertical. The transfer device consists of a head 12 carried by guide arms 13 and operated by fluid pressure cylinders 14.

The mill shown in Figs. 6 and 7 consists of 40 two horizontal stands of rolls A and B separately driven and arranged in different lines of feed and a stand of vertical rolls arranged in tandem to one of the stands of horizontal mills and is driven from the 45 motor employed for operating the other stand of horizontal rolls. In this mill two independent feed tables E and F are employed, the rollers of which will rotate constantly in the same direction as the rolls to 50 which they feed and from which they receive the article. The article is transferred from one feed table to the other by means of a pushing mechanism substantially such as that shown in Fig. 1, the article passing over 55 rails 15 connecting such lines of feed rollers. In operating this mill the article will be placed on the table E of the stand of rolls A and will be fed thereby between such rolls. During reduction by rolls A, the rolls B 60 and C will be idle and although the rolls C

are designed to be operated by the motor of rolls A, such motor will not be called upon to do any work with the rolls C while the article is being reduced by rolls A as the rolls C are in the line of feed of the rolls B. 70 When the article is transferred onto the table F for the rolls C and B, it will be carried by such feed rollers between such vertical rolls, and then between the rolls B. During this movement of the article the 75 rolls C will be operated by the motor of the rolls of stand A and the rolls B by their own motor, so that although the article is at this time being operated on by both stands of rolls, each stand will be independently 80 driven by a separate motor whose only load will be that of the rolls operating on the article. It is characteristic of this arrangement that although three stands of rolls are driven by two motors, the latter are not 85 overloaded, but each is called upon to operate only one stand of rolls at a time.

I claim herein as my invention:

1. In a rolling mill the combination of two stands of horizontal rolls arranged out 90 of line with each other, means for rotating the rolls of the respective stands in opposite directions, feed mechanism, means for operating such mechanism alternately in opposite directions and means for laterally shifting the article being rolled from the line of delivery of one stand of rolls to the line of feed of the other stand of rolls.

2. In a rolling mill, the combination of two stands of horizontal rolls arranged out 100 of line with each other, feed mechanism, a motor, connections from said motor to said stands of rolls constructed to rotate said rolls in opposite directions, the connection from the motor to one stand of rolls being 105 arranged respectively above and below a portion of the feed mechanism, means for operating the feed mechanism alternately in opposite directions and means for laterally shifting the article being rolled from the line 110 of delivery of one stand of rolls to the line of feed of the other stand of rolls.

3. In a rolling mill, the combination of two stands of horizontal rolls arranged out 115 of line with each other, means for rotating the rolls of the respective stands to feed the article in opposite directions, vertical rolls arranged in line with one of the stands of horizontal rolls, mechanism for feeding the article being rolled to the horizontal rolls, 120 and means for shifting the article from the line of delivery of one stand of rolls to the line of feed of the other stand of rolls.

4. In a rolling mill the combination of two stands of horizontal rolls arranged out 125 of line with each other, both as regards the line of feed and axially, means for driving the rolls of one stand in one direction and those of the other stand in the other direction, vertical rolls arranged in operative re- 130

lation to both stands of horizontal rolls, driven feed rollers arranged to deliver the article to and receive it from the several stands of rolls, and means for shifting the article being rolled from the delivery side of one stand of rolls to the line of feed of the other stand of rolls.

5. In a rolling mill the combination of two stands of horizontal rolls arranged out 10 of line with each other both as regards the line of feed and axially, three vertical rolls arranged in operative relation to both stands of horizontal rolls, means for adjusting the outer vertical rolls relative to the intermediate roll, driven feed rollers arranged to deliver the article to and receive it from the several stands of rolls and means for shifting the article being rolled from the delivery side of one stand of rolls to the line of feed 15 of the other stand of rolls.

6. In a rolling mill the combination of a

stand of two-high rolls and a stand of three-high rolls arranged out of line with each other, both as regards the line of feed and axially, a motor, connections from said 25 motor to said stands of rolls constructed to rotate the rolls of one stand to feed the article therethrough, and a roll of the other stand in the direction of movement imparted to the article by said rolls, and the second 30 roll, of the second stand in reverse direction, feed mechanism and means for laterally shifting the article being rolled from the line of delivery of one stand of rolls to the line of feed of the other stand of rolls. 35

In testimony whereof, I have hereunto set my hand.

JOSEPH FAWELL.
